CLAIM

The ornamental design for a separator for a ball bearing, as shown and described.

DESCRIPTION

FIG. 1 is a front elevational view of a separator for a ball bearing according to our new design, the rear elevational view being a mirror image of that shown;

FIG. 2 is a left side elevational view thereof, the right side view being a mirror image of that shown;

FIG. 3 is a top plan view thereof, the bottom plan view being a mirror image of that shown;

FIG. 4 is a longitudinal sectional view taken along line 4-4 in FIG. 1; and,

FIG. 5 is a perspective view thereof.
